(57) **CLAIM**

The ornamental design for a card wallet, as shown and described.

DESCRIPTION

FIG. 1 is a front perspective view of the card wallet showing my new design, according to a first embodiment;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, showing inside of the card wallet;

FIG. 9 is a front perspective view of the card wallet showing my new design, according to a second embodiment;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a perspective view thereof, showing inside of the card wallet.

The broken lines on the wallet represent stitching that forms part of the claimed design.
